GEORGE HENRY LLOYD, OF HOUSTON, TEXAS.

RECORD FOR LIVE-STOCK AND OTHER SHIPMENTS.

1,277,325

Specification of Letters Patent. Patented Aug. 27, 1918.

Application filed November 21, 1916. Serial No. 132,674.

To all whom it may concern:

Be it known that I, GEORGE H. LLOYD, a citizen of the United States, residing at Houston, in the county of Harris and State 5 of Texas, have invented a new and useful Record for Live-Stock and other Shipments, of which the following is a specification:

This invention has reference to records for live stock and other shipments by rail- 10 roads or other common carriers, and its ob- ject is to provide records of shipments of such a nature as to show all necessary or permanent conditions of the shipment and of the carrying means at the place of re- 15 ceipt, during transportation, and at the place of delivery, with such duplication of the records and gathering of the same that full information of every shipment may be obtained at any time for the adjustment of 20 claims and the location of responsibility for damage, if any.

In accordance with the present invention the records are so arranged that the possibility of collusion for the falsification of the 25 records, or the successful falsification of the records in any way is so completely eliminated that an assembled set of reports of a shipment from the point of origin to the point of delivery will be necessarily wholly 30 credible, and acceptable as a true record without question, wherefore any claims for damages can be safely settled without further evidence.

The invention comprises various report 35 sheets, certain of which are to accompany the usual way-bill issued by the railroad or other common carrier, showing both the condition in detail of the shipment as received and the condition in detail of the 40 equipment. In addition to this, the system includes daily reports showing the condition of the shipment and the equipment as the shipment proceeds toward the destination, and the condition of the shipment at 45 the destination, and a detailed report as to the condition of the shipment as received by the consignee.

The invention which is applicable to different kinds of shipments and to different 50 modes of transportation, is particularly valuable in connection with the shipment of live stock, by which term it is intended to cover all kinds of live stock, including horses and mules, and smaller animals, and also animals more specifically included under the term cattle. 55

Since live stock comes particularly under the designation of perishable freight, the necessity of a careful and complete record of all conditions affecting the shipment becomes of value in determining claims for damages, which claims under present conditions amount to hundreds of thousands of dollars yearly, and which in very large proportion represent preventable losses, both 60 to the common carriers and to shippers and consignees. 65

For the sake of simplicity of description it will be considered that the shipments comprise live stock and the common carrier 70 is a railroad or a series of railroads, and that the shipments are made from stock-yards which in the cattle country are associated with the railroads.

The system includes a blank for a record 75 of the live stock shipments at the point of origin and supplementary to the billing, together with another blank also supplementary to the billing, such blanks being for convenience designated as Nos. 1 and 2, 80 respectively. There is also another blank for a daily live stock report and record of handling, whereby a detailed report of both the condition of the live stock and the equipment or rolling stock, as well as other 85 information, is made out and forwarded to a proper official each day.

The system includes a receipt for the delivery of the live stock and a report of 90 the veterinary inspection where such inspection may be deemed advisable.

The system may also include instructions 95 and other information in printed form useful to officials, employees and others, but not necessary for the working of the system as a preventive against losses due to unjust claims, or inconvenience, or losses to shippers, since the system provides a means whereby the shippers, as well as the carriers, are protected.

The invention will be best understood 100 from a consideration of the following detailed description, taken in connection with the accompanying drawings forming part 105 of this specification, with the further understanding that while the drawings show a practical form of the invention, the latter is not confined to any strict conformity with the showing of the drawings, but may be changed and modified so long as such changes and modifications come within the scope of the appended claims.

In the drawings:—

Fig. 2 is a similar view of another filled in blank of the same live stock shipment at the point of origin and supplementary to 15 billing, and designated No. 2.

Figs. 3 and 3^a together constitute a view of a filled in blank of the same shipment and constituting a daily live stock report and record of handling.

Fig. 4 is a filled in receipt for the delivery of the live stock shipment.

Fig. 5 is a view of a filled in blank constituting a report of veterinary inspection.

The specific showing of the drawings is 25 that of a part of a series of records of a live stock shipment over a railroad or railroads from the point of origin where stockyards are located to the point of destination, and it may be assumed that the journey is 30 sufficiently long to demand one or more unloadings at stockyards for feeding, watering and rest of the live stock.

In order to avoid or very largely diminish unnecessary causes of loss and damage, 35 especially in the case of live stock, which is to an uncommon degree perishable freight, prompt and careful handling and particular care as to the condition of the equipment is necessary. Furthermore, to promptly adjust losses which actually do occur, to avoid the payment of unjust claims, thus protecting the carrier, and to facilitate the payment of just claims, thus protecting the shipper, the necessity of a full and complete record 40 even to minutiae is apparent.

Such a complete record of every shipment, both at the point of origin and during the progress of the shipment over the railroad, is conducive to the maintenance of the 50 equipment in first class order, especially as the responsibility for damage and losses is readily ascertainable and cannot be shirked by any one to whom the responsibility is readily traced.

55 The report No. 1 supplementary to the billing and having to do with the live stock shipment at the point of origin is in the form of a blank 1 shown in Fig. 1 and containing certain printed matter and spaces 60 associated therewith to be filled out by a responsible person at the stockyards or other loading point or railroad freight office.

The blank includes a space 2 for the name of the stockyards and the city and State in 65 which they are located. Also, there is a space 3 to be filled in with the name of the railroad over which the shipment is to be made, or, if it be a large shipping point, certain names are printed in. There is also provided another space 4 wherein is 70 designated the city constituting the loading point.

Another space 5 is provided for the names of the consignor, the consignee, the destination and the routing. Still another space 6 75 is provided for data as to the party ordering the cars, from whom the cars are ordered, when the cars are placed for loading, the number of cars ordered, received and used, the condition of the cars used, how the cars 80 are bedded, and by whom loaded. All this matter may be conveniently placed with some parts printed and others to be filled in, at the upper portion of the blank, considering the blank as somewhat elongated 85 form top to bottom. Then there is provided a space 7 which may be divided off into lines and columns for the car number, initials and contents.

Following the space 7 and arranged below it is another portion 8 with printed matter and blank spaces to show whether or not an inspection was made of the car or cars and by whom, the condition of the weather and of the pens in the stockyards, the bedding facilities, any exceptions and any remarks which may be deemed necessary, and a space for the signature of some responsible person representing the stockyards or railroad carriers. The filled out blank No. 1 90 supplementary to the billing is attached to the way-bill, which latter is assumed to be an ordinary way-bill and hence not shown in the drawings, while the agent at the point of origin retains a carbon copy of blank No. 1 95 for his files.

For a better understanding of the relation of supplementary blank No. 1 to the bill of lading and representing a description of the live stock shipment at a point of 100 origin so far as the equipment is concerned, it appears that the consignor ordered one car from the superintendent of terminals on June 13, 1912, and such car was placed for loading at 4 a. m. on June 14, 1912. The condition 110 of the car was good and was well bedded with clean sand. Furthermore, the car was loaded by the stockyards superintendent at 4.35 a. m. on June 14, 1912, so that the cattle 115 were in the car thirty-five minutes after the car was placed. The blank No. 1 also shows that the shipment was to go from San Antonio, Texas, to Algiers, La., and, furthermore, shows the routing and also gives the 120 number of the car and the initials, which, of course, is in agreement with the way-bill. It further appears that the car was 125 inspected, the weather was hot and dry, and the condition of the pens in the stockyards was good. The name of the car inspector 130 also appears on the blank. It appears from the filled in blank that the bedding facilities consisted of sand.

The filled in blank contained a note to the effect that one of the live stock was lame, and this consisted of a brindle cow lame on loading, thus identifying the particular animal found to be lame, and, therefore, particularly liable to damage and showing that this lameness did not occur after loading, thereby relieving the common carrier from much of the responsibility of damage in this respect. The supplementary form is signed by a suitably authorized person, who therefore becomes responsible for the truthfulness of the report.

The supplementary report No. 1 to the billing therefore is in the main a report of the condition of the equipment provided by the railway and made ready for the receipt of live stock at the stockyards. The same paper also contains a brief statement of the condition of the live stock loaded on the car. This report, however, aside from the statement that in the shipment as placed on the car there is one brindle cow lame contains no information whatever as to the condition of the shipment itself. This is left to the report No. 2 supplementary to billing and made out on a blank 9 shown in Fig. 2, and in most respects differing from the blank 1 shown in Fig. 1. In order to connect the blank No. 9 with blank No. 1, there is provided a space 10 showing that the blank is made out in the local freight office of the railroad and contains another space 11 corresponding to the space 3 of the blank 1 and having the same information therein as does the space 3 in blank 1.

Also appearing on the report blank 9 is a space 12 containing classification and grading lists of live stock. This table includes classification for horses, mules, etc., cattle of different kinds with a separate list of dairy cattle, hogs and swine, sheep and goats, and emigrant stock, with arbitrary symbols for the kinds and grades of stock under each head. In Fig. 2 the minutia of the classification and grading is omitted to save space, although in the actual form such minute description occurs. The full classification and grading will be found in connection with the form shown in Figs. 3 and 3^a and will be hereinafter described with reference thereto.

There is also provided in form 9 a space 13 which when filled in shows the point of origin and the consignor with another space 14 showing the destination and the consignee. The portions of the form or blank 9 already described are located in the upper part of the blank, and below there is arranged another space 15 with columns and lines for car numbers, initials, the kind of contents, the classification and the grade.

The car number and initial agree with the car number and initial appearing in Fig. 1. Since the blank of Fig. 1 has to do with the equipment and blank No. 9 has to do with the character of the shipment, the classification and grading does not appear on the blank of Fig. 1.

In Fig. 2 the filled in blank shows that the car contained twenty-seven cows of classification B2 and grade F. This, as will hereinafter appear, designates that the classification has to do with beef cattle, and the cattle consists of cows. Grade F means that the cattle are fat.

Following the space 15 is a portion 16 of the blank containing printed matter requiring answers and information. The filled in blank in the particular shipment under consideration showed that the stock was of average size and in good condition when loaded on the car, but one animal was lame. The information also states whether the shipment was under the twenty-eight or thirty-six hour Federal law, that the cattle had been driven three miles before loading, that the cattle were fed at 5:30 p. m., on June 13, 1912, that is the evening before they were shipped, and that they were watered at the same time. Feed and water were both available at the loading point, the pens were good, the weather was hot and dry; that the load and count was the railroad load and count and not the shipper's load and count; that no full cars were transferred after loading, nor was any part of the load transferred to another car; that the bedding was good and consisted of dry sand, and that the cars were well bedded but not rebedded; that the cars were neither crowded nor overloaded, and that no one was placed in charge of the stock en route. If further appears that the information as to the stock was furnished by the shipper and also was received by telephone from the foreman or superintendent of the stockyards whose name appeared on the supplementary report No. 1. The whole report is signed by the bill clerk of the local freight office, or might have been signed by any other responsible person. The original of the supplementary report No. 2 is attached to the way-bill while the local office retains a copy for the local office files.

Now the shipment goes forward, the way-bill and the two original supplementary reports attached to it also going forward, with copies of these reports retained at the offices where they are made out, so that should the way-bill and originals of the reports be lost the copies will still remain.

There is also made out another report upon a blank 17 shown in Figs. 3 and 3^a and designated Daily live stock report and record of handling. This report is made out at the place of shipping partly by a representative of the stock yards and a railroad official, which parties in the particular illustration comprise the superintendent of the stockyards and the local freight agent whose signatures appear in the proper space 18 provided for them on the blank 17.

- 5 The blank 17 contains a space 19 showing the name of the railroad and another space 20 for the date and the name of the city and state, the date to agree with the date on which the shipment was loaded on to the car.
- 10 The blank 17 contains a printed classification and grading of live stock arranged in a space 21. The live stock is classified in to horses, mules, etc., with the grades including fat, medium, small, poor and rough for 15 horses, and the same grades, with the addition of heavy, for mules. The horses are classified as to various characters and are arbitrarily designated as H1, H2, &c., under the classification. The mules are likewise 20 classified and are arbitrarily designated as M1, M2, etc. The grades are indicated by the initials of the name describing the grades.

Cattle are generally classified under beef 25 cattle, with the arbitrary designation B1, B2, etc., for the kinds of cattle, and are further classified as stockers and feeders with the arbitrary symbols C1, C2, etc., for brief classification. The grading is similar to that for horses and mules, with the 30 grades designated by letters forming the initials of the grade names. Dairy cattle are classified by kinds, with the arbitrary initials D1, D2, etc., and the grades follow 35 the initials of the names of the grades. Hogs and swine are classified and graded like the horses and cattle, and sheep and goats are similarly classified and graded, and similarly designated as is the case with the other 40 live stock. Emigration stock follows the designation of other live stock.

Such classifications and gradings are sufficient for all practical purposes.

Since the form 17 contains a large amount 45 of information and may cover the report for all shipments for a single day, it is necessarily of comparatively large size. There is provided a portion 22 of the form or blank constituting the larger portion of the blank 50 and divided off into lines and columns for a very complete report of the stock and the happenings with respect thereto during transportation including the time between shipment from one stockyard to the next 55 where the cattle are unloaded for rest, watering, and feeding and reloaded for further transportation. The blank 17 contains consecutive columns in which is reported the condition of the stock on arrival whether 60 good or bad, the day and time of arrival and the number and designation of the road engine, so that it can be shown whether or not there was delay in handling, the car number and car initial, the unloading time 65 from the time the car was placed for unloading until it was finished, the date, whether or not the car was inspected and other information, the pen number in which the cattle were located and whether the pen was an open or a shed pen, the total number of 70 live stock checked, the description thereof, which in the present instance is cows, whether animals were tied in the car, the classification and grade, the number down in the car on arrival, the dead in the car on 75 arrival or unable to reload, the down in pen or dead in pen. Also the total number of head forwarded, the condition of bedding in the car, whether or not the car was rebedded, and conditions about a transfer car 80 if any, the number of men in charge, if any, the reloading time, when commenced and finished, and when the car pulled out, the date, the number and designation of the switch engine, the foreman's initials so as to 85 locate responsibility, feeding charges and whether or not paid and to whom, whether or not these feeding charges are to follow, the amount, and kind of feed so as to show the treatment of the cattle, the rate and 90 freight and whether or not it was prepaid, the advance charges, and whether or not the bill of lading was attached, the point of origin and from what railroad, the destination, the routing, the condition of pen and 95 of weather, whether the stock was inspected by a veterinarian, the time of arrival in the railroad yards after reloading, time of delivery to connecting line, the time of departure, thus showing any undue delay, the condition and record of the seals, and any remarks, which in the particular daily report shown in Figs. 3 and 3^a includes the statement that there was one brindle cow lame 100 on loading, and this cow was driven in lame. 105 The report is signed by responsible officials and then forwarded to an official by whom all the records are kept, in this particular instance appearing as the freight claim agent of the originating line with the name 110 and designation shown in the space 18.

The same kind of a daily report is forwarded each day from each unloading and loading point, so that there is a continual record of conditions as to when and how the 115 live stock is received at an unloading point, the feeding, watering and resting of the live stock, the time of reloading, the conditions of the equipment, and the condition of the cattle, so that as the cattle travel toward the destination there is a constant incontrovertible record in which there are so many different people engaged and at such widely different points as to preclude any liability of collusion to defraud anybody. Should any discrepancies appear they are caught up so quickly because of the daily reports sent to an official responsible for their inspection and comparison, as well as storage, that these discrepancies may be investigated at 120 125 130 135 140 145 150 155 160 165 170 175 180 once and the real conditions ascertained before sufficient time has elapsed for them to be forgotten.

If the distance over which the cattle travel is short, the shipment may need but one daily report of handling. If the shipment extends over a considerable distance including two or more days, there will be daily reports corresponding to the number of unloading points, all made on the same kind of blanks or forms and varying only with respect to the conditions to be reported.

There is also provided a form or blank shown in Fig. 4 at 23. This form constitutes the receipt for the delivery of the live stock. This receipt contains a space 24 for a designation of the stockyards which the cattle reach for delivery to the consignee, and another space 25 in which the railroad is named. The receipt also contains a space 26 for a description of the stock and another space 27 in which appears the printed classification and grading of the live stock, so that the consignee, as well as the freight agent, may verify the grading of the stock.

In the particular showing of Fig. 4 it appears that the number of cows received was twenty-six, while the way bill calls for twenty-seven, so that the delivery was one cow short. In the remarks it appears that this one cow was left at a certain station, since it could not be reloaded. From another portion 28 of the receipt it appears that the other stock was in good condition. The receipt contains a notation at 29 as to the time of delivery, another notation 30 as to the name of the party making the delivery, another notation 31 as to whom the shipment was delivered, and still another notation 32 as to the authority for the delivery of the shipment, all these different notations being properly signed so as to locate responsibility.

In order that the cause of damage, if any occurs, may be ascertained, the system includes a report blank 33 shown in Fig. 5. This report blank is that of veterinary inspection. There is provided a space 34 for the name and residence of the veterinary surgeon, a space 35 for the name of the railroad, a table 36 giving the same classification and grading of live stock shown in Figs. 3 and 3^a in detail, and a space 37 divided up into lines and columns to be filled out with the report of the veterinarian. The veterinarian's report includes the date, time of inspection, the car number and initial, the character of the pen in which the cattle were inspected, the number of heads inspected, and the kind of stock, together with classification and grade. The report also includes an indication of the general condition of the stock, whether or not any are down in the car, and the probable cause. Also whether any are dead in the car or down or dead in the pen, and the probable cause. In another column, there is provided space for a notation as to whether any injured cattle could or could not be reloaded and the extent of the injury. The report blank also contains other columns for other items as shown in the drawing, and a space for any remarks, if needed.

The veterinarian's report when made out is signed by the veterinarian and countersigned by the proper officer where the inspection was made, and the original of the report is forwarded to the freight claim agent, considering such official as the one to whom all the reports are forwarded.

It will be understood, of course, that the original of the veterinarian's report is sent to the freight claim agent, while copies of the report are kept by the veterinarian and also forwarded to the agent or superintendent handling the shipment in transit.

Furthermore, not only are the originals of all reports forwarded at once or ultimately to the general freight claim agent, but each person making a report retains a copy, preferably a pencil copy to avoid smearing, while carbon copies are forwarded to other officials, so that there are always enough copies in existence to avoid complete loss of the records should any one or more sets of records be destroyed, the number of records made being sufficiently great to preclude the liability of total loss of all sets of records.

Of course, at each unloading and reloading a suitable report is made and the originals and copies are forwarded and retained as stated.

By the system an ordinary shipment is handled and reported upon by so many different people at widely different localities that the possibility of collusion for false reports is out of the question. Moreover, any discrepancy in the reports is caught up so quickly that the cause of the discrepancy may be discovered while the event is fresh in the minds of those responsible for the handling of the shipment. The responsibility all along the line is quickly located, so that claims may be adjusted in fairness to both the shipper and the carrier.

In the particular shipment shown in the drawings it is at once apparent that the loss in the shipment was not due to negligence on the part of the common carrier, because the one animal was, when loaded, in a condition making it particularly liable to injury and, consequently, the responsibility would be likely to rest mostly either upon the stockyards at the point of origin or upon the shipper.

Moreover, the specific reports make it possible to minutely show the condition of the shipment from the receipt to delivery, identifying the point of injury or loss if such occur, and the cause of such injury or loss, thus greatly facilitating all adjustments for damages and enabling the railroads or other carriers to promptly and fairly adjust all claims from records which if kept according to the system are convincing records and would quickly discourage any attempts at false claims.

A shipper has a right to expect prompt and efficient service. Whether this is given or not can be ascertained from the form entitled Supplementary to billing No. 1, and others of the reports.

The carrier is benefited by a record as to the exact condition of the shipment at the point of origin, this being shown by the form entitled Supplementary to billing No. 2. This also fixes upon the shipper the necessity of delivering the stock for shipment in good condition and to avoid overloading, since neglect in such cases will specifically appear in the record.

As the shipment proceeds the daily live stock report and record of handling specifically furnish all essential information as to the movement of the live stock at all loading and unloading points. The daily report avoids a vast amount of unnecessary correspondence, since it combines a wide range of information in form for ready reference.

The classification and grading of stock is of importance in settling disputes as to damage and for other purposes.

When the stock arrives at the destination there has already reached, or is in process of transmission to the freight claim agent or other proper official to have charge of such reports, a full and complete record of the shipment, detailing the condition of the equipment and the character by classification and grading of the shipment as well as notations with respect to any untoward incident which may have occurred. Since the system contemplates a series of local records affecting local agents, as well as a system of records covering the whole shipment from beginning to end, it becomes an easy matter to locate responsibilities and to rectify apparent discrepancies as well as to at once determine the character of actual damages, should such occur, and the quick adjustment of any claims which might arise from such damages. Furthermore, the completeness of the records prevents any attempts at wrongfully claiming damages, since a wrong claim can be at once refuted. In the ordinary course of handling live stock, and, in fact, other shipments, it is often a matter of great expense and a long lapse of time to arrive at even an imperfect conclusion without the conclusion having any special weight because of the lack of exact proof.

With the system of the present invention the proof is of an incontrovertible nature, convincing to both the shipper and the carrier, so that adjustments may be made quickly and fairly to all parties concerned. In fact, the chain of records is so complete and the value of the shipment so readily fixed that it cannot be disputed.

The various forms are, of course, in great part printed with spaces for filling in such information as may be necessary and proper. The forms also contain printed instructions which, however, have not been displayed on the drawings, since such instructions are not necessary to an understanding of the invention.

While the system has been described with particular reference to the shipment of live stock, and is particularly valuable in connection with such shipments, it will be understood that the system is valuable in connection with other shipments than live stock, and in such case the printed matter must, of course, vary in accordance with the general character of the shipments.

The value of the system is especially exemplified in the means whereby the shipments are minutely classified and graded and the value of the shipments is thereby established within reasonable accuracy. Moreover, in the case of perishable freight, and particularly such perishable freight as live stock, the system provides for a complete record of all ordinary and untoward incidents placing responsibility where it belongs and relieving both the shipper and the carrier, and especially the latter, from responsibilities which frequently result in the payment of heavy damages by the carriers because of the inability of proving freedom from such responsibilities.

The system reduces loss and damage claims to a minimum because it establishes complete records, because it establishes values, and because it fixes responsibility, and thereby automatically improves the service.

The system includes a series of forms, some of which are of prime importance and some of which are of a nature to bridge over gaps which might otherwise occur in the working of the system, although oftentimes the system will work perfectly without the additional forms.

A highly important feature of the system resides in the concentration of the original records of the shipment en route into the hands of one invariable and responsible official of the originating line, so that such records are always readily speedily accessible to all interested parties.

What is claimed is:—

1. A series of inter-related forms for records of live stock and other shipments by common carriers, consisting of a form supplementary to billing and provided with designated spaces for describing the condition of the equipment at the point of origin, said form to be signed by a responsible person, another form also supplementary to billing and provided with designated spaces for describing the condition of the shipment at the point of origin to be signed by an official 5 of the common carrier, a form with designated spaces for describing the condition and handling of both the equipment and shipment en route, to be filled out and signed at chosen intervals by various officials at the 10 points touched, and still another form to constitute a receipt for the delivery of the shipment, to be signed by the consignee, the several forms constituting a complete record 15 of the shipment for use in adjusting claims against the common carrier.

2. A series of inter-related forms for records of live stock shipments by common carriers, consisting of a form supplementary to billing and provided with designated 20 spaces for describing the character and condition of the equipment at the point of origin, and also conditions material to the transportation of live stock, said form to be signed by a responsible person, another form 25 also supplementary to billing and provided with designated spaces for describing the condition and the treatment of the shipment at the point of origin, said form to be signed by an official of the common carrier and also containing a table for the description of the shipment by symbols, another form with a table like that of the second named form and said third form being provided with designated spaces for describing the condition and the handling of both the equipment and shipment en route, to be filled out at stated times and signed by various officials at the points touched en route, and a receipt for the delivery of the shipment, to be signed by the consignee, said receipt containing a table like those of the second and third named forms and provided with designated spaces for the identification of the shipment, the several forms constituting a complete record of the shipment for use in adjusting 45 claims against the common carrier.

In testimony that I claim the foregoing as my own I have hereto affixed my signature in the presence of two witnesses.
